UNITED STATES PATENT OFFICE

HUGO W. WEIMER, OF MILWAUKEE, WISCONSIN

ROTARY SCREEN

Application filed August 26, 1925. Serial No. 52,545.

This invention relates to rotary screens or trommels. In such screens the material to be screened is introduced at one end and the oversize is discharged at the other.

5 In some instances, more particularly in the lighter sizes, the screens are supported by a central shaft passing through the screens carrying spiders to which the screens are secured. These spiders interfere with the progress of 10 the material through the screens.

In other forms of construction the screens are carried by an outer frame which is rotatably mounted on rollers either under both ends or at the feed end only.

15 There are several objections to mounting a screen on rollers. First it requires careful adjustment to secure proper alignment of the screen and the rollers. Further, the bearing surfaces are exposed and if a piece of rock 20 should fall between the roller and the roller track on the screen frame the screen frame would be raised with the liability that the screen would either be wrenched or possibly completely thrown out of position.

25 One of the principal objects of this invention is to provide a screen which is free from such defects.

Other and further important objects of this invention will be apparent from the dis- 30 closures in the specification and the accompanying drawings.

This invention (in a preferred form) is illus- 35 trated in the drawings and hereinafter more fully described.

35 On the drawings:

Figure 1 is a longitudinal section through a rotary screen embodying the principles of my invention.

Figure 2 is an end view of the feed end of 40 the screen.

Figure 3 is a section on the line III—III of Fig. 1.

As shown on the drawings:

There is shown a screen comprising a 45 plurality of sections, 1, 2 and 3, each having openings of progressively increasing diameter. Outside this screen running longitudinally thereof are angle bars 4. The screens are attached to these angle bars by segmental 50 members 5 riveted or bolted to the screens

and to the angle bars. The screen sections are further joined together by T section angle tie bars 27. At the feed end of the screen the angle bars are bolted to a ring or head 6. A trunnion 22 is formed on said head 6 and is adapted to be journaled in a bearing 7 instead of resting on the usual rollers. A split, removable shell of Babbitt metal 23 forms a circular bearing surface for said trunnion. The bearing is provided with 60 an oil or grease reservoir 8 having a hinged cap 9 therefor.

At the discharge end, which is preferably lower than the head end, the angle bars are extended beyond the end of the screen and 65 bolted to a disc or head 10. The disc or head 10 has inwardly projecting V-shaped extensions 28 spaced 90° apart around the circumference to which the angle bars 4 are secured, as by bolts 29. A spacer 30 is secured to each ex- 70 tension 29 by bolts 31. Each spacer has a leg 32 adjacent the extension 28 and a leg 33 at right angles thereto which latter leg fits be- 75 tween the extension 28 and the ends 34 of the screen. The screen is thereby spaced from the disc 10 leaving openings 35 between the disc and the screen for the discharge of oversized material. A hub or trunnion 11 integral with head 10 is journaled in a stationary bearing 12, said hub being prefer- 80 ably hollow to permit the passage of a water spray pipe therethrough. The bearing 12 is provided with a split bearing shell 24 prefer- 85 ably of Babbitt metal. A thrust ring 25 is mounted on the trunnion 11 between said bearing 12 and a flange 26 on said trunnion to take care of the end thrust due to the in- 90 clination of said screen.

The screen, being mounted in bearings at both ends is always in perfect alignment and 95 there is no chance of the screen being thrown out of position by stray pieces of rock or other articles.

The screen is driven by means of a bevel gear 13 bolted to the disc 10. In mesh with this bevel gear is a bevel pinion 14 on a shaft 15 carrying a driving pulley 16.

For feeding the material to be screened into the screen, a trough-shaped feed spout 17 is provided extending inside of the large 100

diameter trunnion 22. Adjacent the end of the feed spout is an inclined liner 18, conveniently formed of hardened steel to prevent excessive wear on the forward end of the 5 screen.

After passing over the liner 18 the material strikes the finest of the screen sections which removes the smallest particles. The latter after passing through the screen 1 fall 10 onto another and still finer screen 19 arranged concentrically with the screen 1 and spaced therefrom. The screen 19 is supported by a series of V-shaped brackets 20 bolted to the angle bars 4 and to the screen 19.

15 The oversize passes along to the end of screen 3 and is discharged through the openings 35 left between the end of the screen and the disc 10.

If desired the fine dust may be drawn 20 through the hollow trunnion 11 and discharged into a cyclone or other form of dust settling apparatus.

I am aware that numerous details of construction may be varied through a wide range 25 without departing from the spirit of this invention, and I, therefore, do not purpose limiting the patent granted, otherwise than as necessitated by the prior art.

I claim as my invention:

30 1. A rotary screen comprising a perforated sectional cylinder having an uninterrupted internal passage therethrough, V-shaped angle bars extending longitudinally of said cylinder, segmental hoops secured to said angle bars and cylinder for joining the sections of the cylinder together, a closure disc at each end of the cylinder, trunnions integral with said discs, stationary bearings holding said trunnions in alignment, the trunnion at 35 one end of the cylinder defining a relatively large opening providing an adit for material to the screen, an inclined hardened steel liner surrounding the inner wall of the feed opening, the trunnion at the opposite end of the cylinder defining a relatively small opening, the disc at said latter end of the cylinder being spaced from the end of the screen, and exit means between said disc and screen for discharging oversize from said cylinder.

40 2. A rotary screen comprising a perforated sectional cylinder having an uninterrupted internal passage therethrough, V-shaped angle bars extending longitudinally of said cylinder, and a substantial distance beyond 45 one end of the same, segmental straps secured to said bars and cylinder to join the sections thereof together, an end disc having a large diameter hollow trunnion secured to said cylinder and angle bars at one end thereof, a second end disc having a small diameter hollow trunnion secured to the extension of said angle bars, stationary bearings for said trunnions, and exit means between said second end disc and cylinder for discharging oversize 50 from the cylinder.

3. A rotary screen comprising a perforated cylinder, angle bars secured to the cylinder and extending beyond one end of the same, a closure disc having a relatively small diameter hollow trunnion secured to the extension 70 of said angle bars, a closure disc having a relatively large diameter hollow trunnion at the opposite end of said cylinder, said trunnion providing adit means for material to the cylinder, and stationary bearings for receiving said trunnions to maintain the same in alignment.

In testimony whereof I have hereunto subscribed my name.
